UNITED STATES PATENT OFFICE.

EARL A. HECHT, OF MANSFIELD, OHIO.

DESIGN FOR A TIRE TREAD.

Application filed December 1, 1921. Serial No. 519,296. Term of patent 14 years.

To all whom it may concern:

Be it known that I, EARL A. HECHT, residing at Mansfield, in the county of Richland and State of Ohio, a citizen of the United States of America, have invented a new, original, and ornamental Design for a Tire Tread, of which the following is a specification, reference being had to the accompanying drawing, forming a part thereof.

In the drawing Fig. 1, represents a plan view of a portion of the periphery of the tire and Fig. 2 a cross-section of Fig. 1 on the line 2—2.

I claim:

The ornamental design for a tire tread as shown.

EARL A. HECHT.

In the presence of—
RUTH SNYDER.
